[57] ABSTRACT

A dual facing booth having a clip-on bracket assembly for fastening the seats to the framework and a unique one-piece construction for mounting both booths and the table on a single framework.

UNIT CONSTRUCTION BOOTHS

BACKGROUND OF THE INVENTION

In the prior art, booth structures have generally been manufactured and shipped to the installation location where they must be assembled in place. Some type of framework is provided upon which the seats are fastened. Generally the framework is designed to break down into a relatively compact structure for easy shipment. The seat portions themselves are stacked one within another in order to provide a compact shipping package. The assembly operation at the installation site requires that the seats be fastened securely to the assembled framework. In the past this has generally been done by providing brackets which must be laboriously screwed into the seat portion. This assembly procedure is time consuming and expensive since the brackets must be carefully located in order to properly assemble the unit booth. Furthermore, many times the frame has to be positioned in place beforehand and the screws inserted from the underside of the seat portions. This requires a very difficult working position. The workman have to crawl underneath the booth and mark, drill, and insert screws in a large number of holes from underneath the bench. This adds to the cost of installation enormously.

It would be most advantageous if the seats could be prepared at the factory so that they could simply be bolted or clipped onto the framework at the installation site. Such an operation would insure that all of the mounting brackets would be positioned correctly on the seat portions and anchored securely. This would also eliminate the necessity of a difficult assembly procedure at the installation site and thus reduce the overall cost of the booth. My invention provides such an arrangement as described hereinafter.

SUMMARY OF THE INVENTION

Briefly, my invention contemplates the provision of relatively flat brackets which are screwed onto the bottom of the seat portion at the factory. These brackets are raised only slightly so as to permit the insertion thereunder of a tab from a secondary bracket which is used to secure the seat portion to the framework. Since the bracket that is screwed to the seat portion is relatively flat overall it does not interfere with the stacking process and the booth can still be shipped to the installation site in compact economical packages. It may therefore be seen that it is an object of my invention to provide an improved booth structure which because of specially designed seat clips can be easily installed and assembled at a minimum of labor cost. Further objects and advantages will become apparent upon consideration of the following description and drawings.

BRIEF DESCRIPTION OF THE DRAWINGS

FIG. 1 is a side view of the booth construction of my invention.

FIG. 2 is a perspective view of the framework of the booth of my invention with most of the seat portion cut away to better display the framework.

FIG. 3 is a detail sectional side view of the seat portion of the booth showing the unique clip assembly for fastening the seat portion to the framework.

FIG. 4 is a perspective view of the special generally flat bracket that is mounted on the seat portions at the factory.

FIG. 5 is an underside view of a cutaway portion of one seat showing the general location of the mounting brackets relative to the framework assembly.

DESCRIPTION OF THE PREFERRED EMBODIMENT

10 In FIG. 1 an end view of the assembled booth construction of my invention is shown. Two bench seats 10 and 12 are shown mounted on the framework. Generally seats 10 and 12 comprise preformed molded bench seats constructed from laminated layers of wood and plastic in a manner well known to those skilled in the art. These laminated seats 10 and 12 are supported on a framework by means of unique clip-on bracket assemblies 14 and 16. Clip-on assemblies 14 and 16 will be described in detail later with respect to FIGS. 3, 4 and 5.

15 The configuration of the frame assembly may be more readily understood by reference to FIG. 2. In FIG. 2 it may be seen that the supporting framework comprises a pair of rectangular frames 18 and 19 connected together by means of a cross member 20. This unitary structure is supported at four corners by means of legs 21. The entire structure may be welded or bolted together as desired in a manner well known to those skilled in the art. Extending upward from cross member 20 are two upright members 22 which support a pair of angle support members 23. Members 23 support a table top 24 which for the sake of clarity is shown only in FIG. 1. In FIG. 2 only a portion of seat 12 is shown to indicate its mounting position on the framework. The remaining portion of seat 12 and all of seat 10 have been eliminated in FIG. 2 in order to see the structure of the framework.

20 Returning to FIG. 1 it may be seen that upright members 22 are connected to cross member 20 by means of a pair of bolts 25 which pass through member 20 to threadably engage blocks 26 inside of upright members 22. Blocks 26 are welded or otherwise secured to the insides of upright members 22. When bolts 25 are tightened down against washers 27 and member 20 the upright members 22 are held rigidly in place so that table top 24 may be mounted on the support members 23.

25 The design of the supporting framework as depicted in FIGS. 1 and 2 has been found to be particularly efficient and desirable in actual practice. When seated side by side persons utilizing the booth are still provided with a feeling of privacy and separateness because of the middle cross bar 20 which divides the seats. With this construction the booth structure is easy to assemble quickly just by fastening the upright members to the table top and to the cross member 20.

30 In FIG. 3 a sectional detail view of seat 12 and its associated clip-on bracket assemblies 14 and 16 is presented. A pair of relatively flat special brackets 30 are mounted at the factory directly to the seat portion 12. Brackets 30 may be seen in perspective in FIG. 4. Each bracket 30 comprises two fastening portions 31 and a raised central portion 32. The flat portions 31 are provided with screw holes 33 while the raised center portion 32 is provided with a bolt anchoring hole 34 which is threaded. Returning to FIG. 3 it may be seen that brackets 30 are securely mounted to seat 12 by means of screws 36 which are positioned in all of the holes 33

in the fastening portions 31 of brackets 30. At the front of seat 12 frame 18 is fastened to seat 12 by means of bracket assembly 14. Bracket assembly 14 comprises a metal strap having an upright portion 40 and horizontal portions 41 and 42 extending in opposite directions from upright portion 40. Bracket assembly 14 also is provided with another horizontal portion 43 welded to upright portion 40. Horizontal portions 42 and 43 are provided with suitable holes so that a bolt 44 can be inserted through horizontal portion 42 and tightened into a threaded hole 45 in horizontal portion 43. Once bolt 44 is inserted and tightened bracket assembly 14 is rigidly fastened about the forward portion of rectangular frame 18. The horizontal portion 41 extending at right angles from upright portion 40 may be inserted underneath bracket 30 sliding between seat 12 and the raised portion 32 of bracket 30. With horizontal portion 41 inserted underneath the front bracket 30 the rear portion of rectangular frame 18 fits snugly up against the rear bracket 30 at point 35. To insure that rectangular frame 18 remains firmly against the rear of seat 12, bracket assembly 16 is positioned as shown. Bracket assembly 16 comprises a member 50 which wraps around underneath, inside, and then back over the top of rectangular frame 18. Member 50 has a hole 51 therein through which a bolt 52 is inserted. Bolt 52 is threaded into hole 34 in bracket 30 so as to securely hold rectangular frame 18 up against the bottom of seat 12.

It is clear that the steps of mounting bracket assemblies 14 and 16 to the frame 18 and securing them to brackets 30 makes for a much easier process than crawling underneath the bench and screwing in a multiplicity of screws similar to screws 36. Thus, assembly at the installation site is made much easier by the apparatus of my invention. Any number of clip assemblies 14 and 16 may be utilized to mount the seats to the frame. However, in the preferred embodiment it is contemplated that each seat may use four brackets as shown in FIG. 5.

In FIG. 5 a bottom view of seat portion 12 is shown. Four brackets 30 are mounted as shown generally at the four corners. This is easily done at the factory and such factory mounting insures that the benches will be properly aligned and securely anchored when finally installed. Bracket assemblies 14 and 16 are installed as

shown at four locations about rectangular frame 18 so as to provide a completely rigid and secure structure. A similar arrangement is used on seat portion 10.

It may therefore be seen that I have provided a new and improved booth structure which can be shipped compactly and which can be easily and inexpensively installed at the final assembly point. Clearly, it is possible for minor deviations to be made to the structure shown without departing from the scope and spirit of the invention and therefore the following claims are presented to emphasize those novel aspects of the invention.

I claim:

1. A booth assembly comprising in combination: a frame structure for supporting a table and two benches; a pair of benches of similar shape so as to be mutually stackable; a plurality of thin brackets fastened to the underside of said benches, said brackets having slightly raised portions, said brackets being thin so as to avoid interfering with the stacking of the benches; and first bracket clip means operable to engage said frame structure and slip between said benches and the raised portions of at least some of said plurality of brackets, said bracket clip means comprising at the front of the bench a first member bolted around said frame structure with a first extension from said member adapted to slide under the raised portion of one of said plurality of brackets and at the rear of the bench a second member shaped to surround the frame structure with a bolt in said second member adapted to thread into a hole in one of said plurality of brackets.

2. The apparatus of claim 1 including a table supported on said frame structure by means of two vertical members extending down from said table to a single cross member extending between the portions of the frame structure supporting each of said pair of benches.

3. The apparatus of claim 2 in which said two vertical members are hollow and each contains a plug therein with threaded holes in the plugs to accept bolts extending through said cross member.
